WALL MOUNTED RACK FOR KEYS

Jürgen G. Hess, Neuer Weg 2, 7734 Brigachtal-Klengen, Germany

Filed Oct. 2, 1975, Ser. No. 619,035

Term of patent 14 years

Int. Cl. D6—04

U.S. Cl. D6—114

FIG. 1 is a front elevational view of a wall mounted rack for keys showing my new design;

FIG. 2 is a rear elevational view thereof;

FIG. 3 is a side elevational view taken from the left of FIG. 1; and

FIG. 4 is a side elevational view taken from the right of FIG. 1.

I claim:

The ornamental design for a wall mounted rack for keys, as shown.
